(57) **CLAIM**

The ornamental design for headphone, as shown and described.

DESCRIPTION

The file of this patent contains at least one drawing/photograph executed in color. Copies of this patent with color drawings(s)/photograph(s) will be provided by the Office upon request and payment of the necessary fee.

FIG. 1 is a perspective view, of a headphone showing our new design,

FIG. 2 is a rear view thereof,

FIG. 3 is a front view thereof,

FIG. 4 is a left side view thereof,

FIG. 5 is a right side view thereof,

FIG. 6 is a bottom view thereof,

FIG. 7 is a top view thereof,

FIG. 8 is a perspective view of an alternate embodiment of the headphone with the only difference being the color of the cover,

FIG. 9 is a perspective view of an alternate embodiment of the headphone with the only difference being the color of the cover,

FIG. 10 is a perspective view of an alternate embodiment of the headphone with the only difference being the color of the cover; and,

FIG. 11 is a perspective view of an alternate embodiment of the headphone with the only difference being the color of the cover.

The broken lines depict environment that forms no part of the claimed design.

**1 Claim, 11 Drawing Sheets
